(57) **CLAIM**

The ornamental design for a display screen with graphical user interface, as shown and described.

DESCRIPTION

FIG. 1 is a front view of a display screen with graphical user interface shown on a monitor.

FIG. 2 is a front view of the display screen with graphical user interface shown on a monitor, with the design shown in another environment.

FIG. 3 is a rear view of the monitor.

FIG. 4 is a top view of the monitor.

FIG. 5 is a bottom view of the monitor.

FIG. 6 is a right side view of the monitor.

FIG. 7 is a left side view of the monitor.

FIG. 8 is a front view of the display screen with graphical user interface on a second monitor.

FIG. 9 is a front view of the display screen with graphical user interface shown on a second monitor, with the design shown in another environment.

FIG. 10 is a rear view of the second monitor.

FIG. 11 is a top view of the second monitor.

FIG. 12 is a bottom view of the second monitor.

FIG. 13 is a right side view of the second monitor; and,

FIG. 14 is a left side view of the second monitor.

The broken lines in the drawings illustrate portions of the display screen with graphical user interface and environmental subject matter that form no part of the claimed design.
